No. 12,703

Jan. 24, 1882

UNITED STATES PATENT OFFICE.

WALTER M. CONGER, OF NEWARK, NEW JERSEY.

DESIGN FOR A TEA-TRAY.

SPECIFICATION forming part of Design No. 12,703, dated January 24, 1882.

Application filed June 18, 1881. Term of patent 14 years.

To all whom it may concern:

Be it known that I, WALTER M. CONGER, a citizen of the United States, residing in the city of Newark, county of Essex, and State of New Jersey, have invented a new and useful Improvement in Designs for Tea-Trays and Waiters, fully described and represented in the following specification and the accompanying photograph, forming a part of the same.

10 My design is shown in the accompanying fac-simile as applied to an oval tray, but is equally applicable to round trays. The outer flange of the tray being viewed obliquely when photographed, the lines of the design are somewhat foreshortened, and certain straight lines, as the diagonals herein described, appear slightly curved. Radial lines have not heretofore been used in decorating the outer flange of a tray, and the design presented shows an application of such lines as the boundaries of spaces into which the whole flange of the tray is divided. The spaces are shown as alternately black and white, and the bottom of the tray is shown as black, with the exception of 20 a white band or fillet adjacent to the flange, such band being decorated by a row of alternating dots and dashes along the middle of its width. All the spaces upon the flange are decorated alike, the light spaces showing the pattern employed in dark lines, and the intermediate ones in light lines, upon a dark ground, and the pattern being symmetrically disposed upon each side of a diagonal of the space. The diagonal of the space is formed by a row of 30 dots bounded upon each side by a narrow line, outside of which is a scalloped line with its points toward the diagonal and in contact with the oblique lines. In the center of each triangle, upon opposite sides of the diagonal, is 35 a similar scroll-figure.

40 The design shown in the fac-simile was drawn in black and white to photograph clearly; but as it is the form of the design that is claimed and not its color, it is obvious that it may be produced in any desired colors which will produce an agreeable effect. Thus the band bordering the bottom of the tray may be made in gilt, with red lines and dashes, and separated from the flange by a white line.

45 50 The spaces upon the flange may be alternately of black and gold, separated by white

lines, or without any intervening line, and the pattern in the spaces may be gilt or red upon the black spaces and brown or black upon the gilt, or in any other harmonious colors. 55

The narrow boundary-lines may be dispensed with in any part of the design and the divisions be distinguished merely by contrasting colors, and the ornamentation upon the band inside the flange may be omitted or varied at pleasure, as these features are not material to the design, the essential feature of which is the division of the flange into spaces by radial lines, and the decoration of the intermediate spaces, first, by alternate contrasting colors; secondly, by the diagonal arrangement of the pattern in each space; and, thirdly, in the combination, with the flange divided by radial lines, of the band of color upon the bottom of the tray. 70

From the above it will be seen that three contrasting colors may be used in succession upon the spaces if their total number is divisible by three, and that in such case the diagonal pattern may be omitted from the central space in each group of three, as it may be from any of the spaces in the design with two contrasting colors. 75

Having thus fully defined my design, I claim the same as follows:

1. The design, substantially as shown and described, for the flange of a tea-tray, consisting of the spaces divided by radial lines, substantially as herein set forth. 80

2. In combination with the spaces formed upon the flange by radial lines, as herein shown and described, the pattern disposed across the space diagonally, substantially as herein set forth. 85

3. In combination with the flange divided into spaces by radial lines in the manner shown and described, the band of color adjacent to the flange upon the bottom of the tray, substantially as set forth. 90

In testimony whereof I have hereunto set my hand in the presence of two subscribing witnesses. 95

WALTER M. CONGER.
